CLAMP SUPPORT FOR GLOBES

Application filed August 31, 1931. Serial No. 560,342.

This invention relates to a clamp support for light globes whereby the globes are effectively and securely held against displacement, and further, may be readily removed when it is necessary to clean them or replace the light.

An object of our invention is to make it unnecessary to remove or unscrew the screws which are commonly used for the support of light globes. This being accomplished by a novel clip which engages the screw.

Another object is to provide a novel clamp support for globes which is simple in construction, inexpensive to manufacture, which may be readily installed upon existing types of light globes, and which can be placed upon any globe support either of the interior or exterior type. The clips of our support being so mounted that they will always engage the screws in the globe support.

Other objects, advantages, and features of invention may appear from the accompanying drawings, the subjoined detailed description, and the appended claims.

In the drawings

Figure 1 is a top plan view of our support.

Figure 2 is a side elevation of a globe and base with parts broken away to show our support.

Figure 3 is a fragmentary transverse sectional view of the base and the ring.

Figure 4 is a fragmentary side elevation of the supporting ring and a modified form of clip thereon.

Figure 5 is a side elevation of another modified form of clip.

Figure 6 is a side elevation of a further modified form of clip.

Figure 7 is a perspective view of an adjustable type of clip.

Figure 8 is a perspective view of a modified form of adjustable form of clip.

Figure 9 is a plan view of a modified form of clamping ring and the base in which it is held.

Figure 10 is a fragmentary side elevation of a modified form of clamp with parts broken away to show interior construction.

Figure 11 is a perspective view of the frag-

mentary ring and the clip shown in Figure 10.

Referring more particularly to the drawings, the numeral 1 represents a globe of the type commonly used for exterior lighting, such as streets or the like. The globe 1 rests on a support 2 of usual and well known construction. The support 2 is provided with a plurality of screws 3 which heretofore would extend through and engage the globe to hold it in position. When using our ring these screws are threaded out until they merely pass through the support, and do not engage the glass globe.

Due to the imperfection of manufacture, the screws are not accurately spaced apart, but vary in different supports as much as half an inch more or less, also different supports have a different number of screws therein. Our invention consists of applying a band or ring 4 to the globe 1 adjacent to the bottom or top thereof, depending on how the globe is hung. The globe is provided with a flange or bead 5 against which the ring bears. The band is fixedly attached to the globe by means of a screw or the like 6, which screw extends through the over-lapping end of the band. One end of the band is slotted as at 7 and the screw 6 extends through this slot, thus the ring can be expanded or contracted to compensate for different size globes. A plurality of clips 8 are attached to the band 4 or may be integrally formed therewith.

These clips extend over the edge of support 2 and are provided with horizontal extensions 9, which extensions engage the screws 3 so as to hold the globe 1 securely in position. The extensions 9 may be toothed or serrated. They may be formed with a single cam surface as shown in Figure 1, or they may be otherwise constructed as will be subsequently described. A supporting lip 10 is integrally formed on each of the clips 8 and the globe rests on these clips as shown in Figure 3.

Because of vibration, strong wind or other causes the extensions 9 may disengage the screws 3. To overcome this possibility we have arranged a latch 11 which is pivotally secured to the clips 8. This latch is provided with indentations or recesses 12 which

fit over the screw 3 when the latch is swung downwardly, thus the ring 4 is held against any rotary movement, and the clips can not disengage the screws. The clips 8 are formed of spring material so that they will press tightly against the screws, and thus there is little likelihood of any usual force jarring them loose.

In Figure 5 the spring clip 13 is provided with a depending flap 14 which extends on the outside of the support 2, a single hole 15 is formed in the flaps and the screw is passed through this hole. However, it is necessary first to remove the head of the screw in order that this type of clip may be used.

In Figure 6 the clip 16 is provided with a depending flap 17 in which an inclined slot 18 is formed. In this instance, the screw is passed into the slot and the globe is rotated with the ring thereon, so that the screw is forced into the upper end of the slot 18, thus springing the clip down and the screw will be firmly engaged.

The screws in the lamp support are not accurately spaced apart, and also the number of screws vary. Therefore, we have provided a means of adjusting the clips along the ring so as to compensate for these differences. In Figure 7 the ring 4 has attached thereto an outwardly extending bar 19, this bar suitably attached to the ring such as welding or other means. The clip 20 is slidably mounted on the bar 19, one end of the clip being bent around the bar as shown at 21. It will be evident that the clip can be moved horizontally from one end of the bar 19 to the other, or an amount necessary to engage the screw.

In Figure 8 the clip 22 is slidable on the ring itself, that is one end of the clip is bent or formed around the ring 4 as shown at 23.

In Figure 9 the globe base or support 24 is formed with a plurality of rests 25 therein. A wire ring 26 is adapted to encircle the light globe, and the wire is provided with outwardly projecting lugs 27 integrally formed in the wire. These lugs enter the rests 25 and thus hold the lamp globe against displacement. The ends of the wire 26 are connected by means of a toggle clamp 28, this clamp projects through an opening 29 which is formed in the base 24.

In Figures 10 and 11 a wire clamp 30 encircles the globe and the ends of the wire are attached together by a toggle clamp 31. A plurality of spring clips 32 of any type previously described. These clips are slidably mounted on the wire 30, due to the fact that one end of the clip encircles the wire 30 as shown at 33. The clips can thus be moved horizontally to engage one of the screws 3.

Having described our invention, we claim:

1. A clamp support for globes comprising a case in which the globe extends, a plurality of engageable members extending from said case, a globe, a ring, a means securing said

ring about the globe, a plurality of clips extending from said ring, said clips engaging the members extending from the case, and a supporting lip on each clip upon which the globe rests.

2. A clamp support for globes comprising a case, a globe extending into the case, a plurality of engageable members extending from the case, a ring encircling the globe, means securing said ring about the globe, a plurality of clips extending from the ring, a horizontal section on each clip, said horizontal section engaging the said members, and latch means mounted on a clip and adapted to engage one of said members whereby said ring and globe are held against movement.

3. A clamp support for globes comprising a case, a globe extending into said case, a ring encircling the globe, means securing said ring about the globe, a plurality of clips, means slidably mounting said clips on the ring, each of said clips including a horizontal section adapted to engage a member extending from the case.

4. A clamp support for globes comprising a case, a globe extending into the case, a plurality of engageable members extending from the case, a ring encircling the globe, means securing said ring about the globe, a plurality of clips extending from the ring, a horizontal section on each clip, said horizontal section engaging the said members, and latch means mounted on a clip and adapted to engage one of said members whereby said ring and globe are held against movement, and a supporting lip on each of said clips, the globe resting on said lips.

5. A clamp support for globes comprising a case, a globe extending into the case, a plurality of engaging members extending from the case, a wire ring encircling the globe, a clamping means on the ring whereby the ring is held on the globe, a plurality of clips, each of said clips being slidably mounted on the ring, and each clip including a horizontal section adapted to engage said members.

6. A clamp support for globes comprising a case, a globe, said globe extending into the case, a ring encircling the globe, clamp means whereby the ring is held on the globe, a plurality of bars secured to the ring, a clip slidably mounted on each of the bars, said clip being adapted to engage said members whereby the globe is held in position.

In testimony whereof we affix our signatures.
